UNITED STATES PATENT OFFICE.

EDWARD F. RAYMOND, OF SANTA FE SPRINGS, CALIFORNIA.

GUIDE FOR SIDE TRACKERS.

Application filed July 6, 1925. Serial No. 41,655.

This invention relates to a device for use in oil well drilling and more especially in side tracking operations. In drilling wells, tools often become lost as well as other parts in the bottom of the hole and lodge therein so that removal by the usual methods cannot be effected. Such lost parts are commonly termed "fish" and are hereafter referred to by that name. In some of such instances, means are employed to drill around the fish and advance the hole. Such operations are known as "side tracking" and have heretofore been effected by continuing the drilling depending upon the fish to deflect the boring tool to one side. In some instances, the ordinary drilling bits used for this purpose have been changed to suit the individual choice of the driller. A special tool for side tracking is disclosed in my copending application for side tracking tool, Serial No. 13,209, filed March 5, 1925, and the embodiment of the present invention disclosed herein shows and describes a tool of this character as employed with this type of side tracker. The primary object of this invention is to provide a side tracking tool guide which will positively direct the tool laterally of the fish, which will offer a minimum of resistance to drilling, is economical, easy to manipulate, and can be placed quickly in position for use. Another object of this invention is to provide a device of the character described, which may be attached to and form the lower end of an ordinary string of casing. These objects together with other objects and corresponding accomplishments are obtained by means of the embodiment of my invention illustrated in the accompanying drawing, in which:

Fig. 1 is a side elevation of the guide showing a fragment of the casing to which it is attached at the upper end and a fragment of a fish at the lower end; Figs. 2, 3, 4, 5, and 6 are sections as seen on the lines 45 correspondingly numbered in Fig. 1. Referring more particularly to the drawing, a fragment of the original casing in the hole is indicated by 7, and 8 indicates a fish therein. When it is found impossible to dislodge the fish by the ordinary fishing methods, the casing cutter is lowered in the hole and the casing severed as close to the fish as

possible, that is, if the casing cannot be entirely pulled.

A string of casing is now lowered in the hole. Attached to the last joint of the casing indicated by 9 is the guide for the side tracking tool. This guide has a tubular upper end externally threaded so as to receive a coupling collar 10. The upper end of the guide is of tubular form and may be conveniently made of several sections or joints of casing welded together to form a relatively long member, this tubular body being indicated by 11. The wall thereof is cut away at the upper portion as indicated by 12 to form an exit for the side tracking tool. The cut extends substantially into one-half of the tube, and a tapered slot is cut therein ending as indicated by 13 adjacent the lower end of the body.

Secured over the slot and to the body is a concave seat 14 against which the side tracking tool may slide. The seat is provided with perforations 15 to permit the egress of fluid or liquid which may be trapped in the chamber or guide during lowering in the hole. Threaded onto the lower end of the guide is a casing shoe 16 having a perforated plate 17 guarding the chamber. The shoe forms no part of the present invention, and in some instances a coupling adapted to engage casing 7 may be used instead of the shoe.

Drill pipe 18 may have secured to the lower end thereof a conical shaped side tracker 19 which is the boring tool. After the string of casing 9 with the attached guide has been lowered in the hole to position, cementing or any other desired operation may be performed. During the lowering, the hole being filled with slush, the latter enters the chamber in the side tracker guide and may readily pass outwardly through the perforations 15 thereby adding no resistance to the lowering of the casing. The casing and guide having been positioned ready for the drilling operation, the side tracker 19 is lowered passing through the exit 12 and being diverted laterally in its advance until it has been disposed at the side of the original hole. The hole will thus be side tracked advancing around the side of the fish.

It will be noted that the guide is formed as a continuation of the lower end of the string of casing. It is obvious that although it has been described as built up of several sections of casing, it may be formed of an integral piece or in any other convenient manner.

What I claim is:

1. A guide for side tracking tools comprising a hollow body having a tubular upper end with a lateral exit opening and a perforate seat extending in front of said opening and inclined outwardly along the length of said body to the end of the outer periphery thereof, said body having a tubu-

lar open lower end and said seat having perforations for the passage of liquid therethrough.

2. A guide for side tracking tools comprising a hollow body having externally threaded open ends, said body being tubular and provided with a lateral exit opening and a perforate concave seat extending in front of said opening and inclined outwardly along the length of said body to the outer periphery thereof.

In witness that I claim the foregoing I have hereunto subscribed my name this 26th day of June, 1924.

EDWARD F. RAYMOND.
